Attorney.

UNITED STATES PATENT OFFICE.

KENNETH F. MATTHEWS, OF WAUKESHA, WISCONSIN, ASSIGNOR TO THE R. L. KENYON COMPANY, OF WAUKESHA, WISCONSIN, A CORPORATION OF WISCONSIN.

DESIGN FOR A PHONOGRAPH-CABINET.

52,101.

Specification for Design.

Patented June 11, 1918.

Application filed March 2, 1918. Serial No. 220,059. Term of patent 7 years.

To all whom it may concern:

Be it known that I, KENNETH F. MATTHEWS, citizen of the United States, residing at Waukesha, in the county of Waukesha and State of Wisconsin, have invented a new, original, and ornamental Design for Phonograph-Cabinets, as shown in the accompanying drawing and described in the following specification.

The drawing is a perspective view of the phonograph cabinet showing the front and one side thereof.

I claim:

The ornamental design for a phonograph cabinet as shown.

KENNETH F. MATTHEWS.

Witnesses:

JOHN J. CROFT,
W. E. HAWORTH.
